UNITED STATES PATENT OFFICE.

JOSEPH G. TRIMBLE, OF MAINEVILLE, OHIO.

CEMENT FENCE-POST.

No. 863,118.

Specification of Letters Patent.

Patented Aug. 13, 1907.

Application filed April 26, 1907. Serial No. 370,381.

To all whom it may concern:

Be it known that I, JOSEPH G. TRIMBLE, a citizen of the United States, residing at Maineville, in the county of Warren and State of Ohio, have invented a new and useful Cement Fence-Post, of which the following is a specification, reference being had therein to the accompanying drawing.

This invention relates to a new and useful cement or concrete fence post; and the object thereof, is to provide a device of this character, having novel means for supporting fence wire.

A further object is to provide supporting means adjustable so as to regulate the space between each fence wire.

15 A further object is to provide a device which is simple in construction and comparatively inexpensive to manufacture.

With these and other objects in view, the invention comprises further combinations of parts and features 20 which will be hereafter described, claimed and illustrated in the accompanying drawings, in which,

Figure 1 is a perspective view of the post, illustrating the principal features of the invention. Fig. 2 is a transverse sectional view of the post, taken on line 2—2 25 of Fig. 1. Fig. 3 is a perspective view of the post with the wire supporting member omitted. Fig. 4 is a perspective view of the wire supporting member 3^a. Fig. 5 is a perspective view of the wire supporting member 4.

Referring specifically to the drawings, 1 designates 30 a fence post, which is made of cement. This post is provided with a dove-tail groove 2, which is designed to receive the fence wire supporting member 3, which is of the contour to conform to the said dove-tail groove as clearly shown in Fig. 3. This fence wire supporting 35 means is provided with a dove-tail groove 4 in which a plurality of beveled blocks 5 are disposed, each block being provided with an eye 6, in which the fence wire is fixed, as at 7; these eyes have screw-threaded shank portions 8, which are designed to engage the blocks 5 40 so as to engage frictionally upon the rear wall of the groove 4, so as to bind the blocks to the post. The groove 4 of the wire supporting member 3, is open at its lower end so as to allow the blocks 5 to be inserted therein prior to the insertion of the fence wire sup- 45 porting member as will be clearly manifest. After the fence wire supporting member has been inserted in its proper position, the metallic flanges 9 are bent over so as to engage the upper end of the fence wire supporting member, as clearly shown in Fig. 1. These flanges 9 50 have their shank portions 10 embedded in the cement of which the post is composed so as to prevent displacement thereof. The flanges 9 are for the purpose of preventing upward movement of the fence wire sup-

porting member as will be clearly understood. When the fence wire supporting member is positioned as 55 shown in Fig. 1, and locked in such position, the blocks 5 are prevented from being removed, as will be understood.

In Fig. 4 is shown a wire supporting member designated 3^a, into which, the eyes 6 can be inserted and 60 which are stationary therein, while in Fig. 5 the eyes are inserted in blocks which are readily adjustable as will be clearly understood.

Having thus described the invention, what is 65 claimed as new and useful is,

1. A cement fence post, said post having a dove-tail groove, a wire supporting member having adjustable eyes designed for insertion in said groove.
2. A cement fence post having a dove-tail groove, a wire supporting member having eyes designed for insertion in 70 said groove, and metallic flanges fixed at the upper end of said post said flanges being adapted to be bent over said wire supporting member to prevent movement of the fence wire supporting member.
3. A cement fence post having a dove-tail groove, a 75 fence wire supporting member having eyes designed for insertion in said groove, metallic flanges, said flanges having shanks being embedded in the upper portion of the post, said flanges designed to be bent over said wire supporting member for preventing movement of the fence wire sup- 80 porting member.

4. A cement fence post having a dove-tail groove, a fence wire supporting member, designed for engagement therewith, said fence wire supporting member having a 85 groove, blocks carried therein, and means for holding the blocks in adjusted position.

5. A cement fence post having a dove-tail groove, a fence wire supporting member, designed for engagement therewith, said fence wire supporting member having a 90 groove, blocks carried therein, said blocks having eyes to which the fence wire is connected and means for holding the blocks in adjusted position.

6. A cement fence post having a dove-tail groove, a fence wire supporting member designed for engagement therewith, said fence wire supporting member having a 95 groove, blocks carried therein, said blocks having eyes to which the fence wire is connected, said eyes having shanks for holding the blocks in adjusted position.

7. A cement fence post having a dove-tail groove, a fence wire supporting member designed for engagement therewith, said fence wire supporting member having a 100 groove, blocks carried therein, said blocks having eyes to which the fence wire is connected, said eyes having shanks which are threaded for holding the blocks in adjusted position, and metallic flanges fixed at the upper end of said 105 post and adapted to be bent over said wire supporting member to prevent movement of the fence wire supporting member.

In testimony whereof I hereunto affix my signature in presence of two witnesses.

JOSEPH G. TRIMBLE.
